DESIGN FOR A STATUETTE

Todd O'Donnell, Chicago, Ill., assignor to Estate of Harold L. De Lisle, a trust, doing business as Engineering Manufacturing Company, Sheboygan, Wis.

Application March 16, 1945, Serial No. 118,518

Term of patent 14 years

(Cl. D29—23)

To all whom it may concern:

Be it known that I, Todd O'Donnell, a citizen of the United States, residing at Chicago, in the county of Cook and State of Illinois, have invented a new, original, and ornamental Design for a Statuette, of which the following is a specification, reference being had to the accompanying drawing, forming a part thereof.

Fig. 1 is a front elevation of statuette showing my new design.

Fig. 2 is a rear elevation of the statuette.

Fig. 3 is a top plan view thereof.

Fig. 4 is a side elevation, looking to the left of Fig. 1.

I claim:

The ornamental design for a statuette, substantially as shown.

TODD O'DONNELL.
